UNITED STATES PATENT OFFICE.

GEORGE H. WILLARD, OF HOPEDALE, MASSACHUSETTS, ASSIGNOR TO DRAPER CORPORATION, OF HOPEDALE, MASSACHUSETTS, A CORPORATION OF MAINE.

LOOM SHUTTLE.

Application filed July 23, 1926. Serial No. 125,335.

This invention relates to loom shuttles and more particularly to the thread delivery control uncoiling engagement type, wherein a control member engages the yarn as it is 5 unwound from the thread package within the shuttle.

It has been proposed heretofore to control the delivery of thread or filling from the shuttle by the use of bristles or brushes within the bobbin chamber which engage the unwinding filling. The brushes or bristles, however, frequently become entangled with the filling and cause breakage. It has been further proposed to secure to the side wall 10 of the bobbin chamber in the shuttle a piece of fabric extending the full length of the filling carrier or bobbin which may, in a measure, at least, control delivery of the filling from the shuttle.

As the filling is withdrawn from the shuttle during weaving, it tends to balloon in the bobbin chamber and such ballooning is generally emphasized near the tip end of the bobbin or filling carrier and often becomes 20 seriously objectionable.

One of the objects of the present invention is to provide a filling uncoiling control member secured to a wall of the bobbin chamber with a bow or bend, inherently flexible, and adapted for engagement with the unwinding filling near the tip portion of the bobbin as the filling is withdrawn from the shuttle during weaving. More specifically stated, the filling uncoiling control member has its ends secured to the same wall of the bobbin chamber at points separated a distance less than the straight length of the filling uncoiling control member, with the 30 result that a bow or bend is formed in said member, which is caused to project inwardly of the bobbin chamber and engage the uncoiling filling, to check its ballooning tendency and yet yield sufficiently to permit the passage of the filling between the filling carrier or bobbin and the control member.

The invention and new features thereof will best be made clear from the following description and the accompanying drawings of one good form thereof.

In the drawings:

Fig. 1 is a plan view of a filling replenishing and self-threading shuttle provided with the present invention, part of the shuttle being broken away;

Fig. 2 is a sectional view of a shuttle provided with the present invention; and 55

Fig. 3 is a cross-section on the line 3—3 of Fig. 1.

The shuttle may be of usual character and comprises the body portion 1 in which is 60 formed the bobbin chamber 2 for the support of the thread package, which, in the present instance of the invention comprises the filling 4 wound upon the bobbin or filling carrier 5. The bobbin holding end of 65 the shuttle is not herein illustrated because it forms no essential part of the present invention and may be as now usual in filling replenishing shuttles. The bottom portion of the shuttle is open, as at 6, to provide 70 for the ejection of the filling carrier or bobbin by the transferring mechanism in the loom.

The front end portion of the shuttle, as indicated in Figs. 1 and 2, is provided with 75 a threading block 7 having a longitudinally extending thread passage 8 with which communicates the side delivery eye 9, and so far as the present invention is concerned, 80 the threading block for effecting automatic threading of the shuttle in the loom may be of any usual or desired type.

In accordance with the present invention, the shuttle is provided with a filling uncoiling control member near the delivery end portion of the shuttle, and such member may be constituted as a flexible cord, braid, string, or other like material, inherently possessed of sufficient self-sustaining 85 qualities to maintain its initial position in 90 the bobbin chamber as will more fully appear.

In the present instance of the invention, the filling uncoiling control member comprises a braid 10, the end portions 11 and 12 of which are secured to the shuttle at the same side of the bobbin chamber. The distance between the points 11 and 12 where the ends of the control member are secured 95 to the shuttle is less than the straight length 100 of the uncoiling control member, with the result that the latter is formed in a bend or bow between the ends 11 and 12, as indicated in Figs. 1 and 2, and the bow or bend normally rests upon the filling carrier or bobbin near the delivery end thereof. When 105 the filling carrier or bobbin contains a large amount of filling, as indicated in Fig. 1, the

filling uncoiling control member may rest partly upon the tip end portion of the bobbin or filling carrier 5 and partly upon the conical end of the filling adjacent such 5 tip, and when the filling has been withdrawn from the shuttle so that the conical portion of the filling wind is no longer engaged by the filling uncoiling control member, the latter will bear upon the surface of the filling carrier or bobbin 5, and in either case, as the filling is rapidly withdrawn from the shuttle during weaving, it will pass between the control member and the filling carrier or bobbin and be restrained in its ballooning 10 tendencies. This is well illustrated in Fig. 2 wherein the filling *a* is shown as being withdrawn from a filling carrier, and at such time it will have a tendency to swing outwardly or balloon during the unwinding 15 process, but inasmuch as the bend or bow of the uncoiling control member rests upon the filling carrier or bobbin, the filling *a* must pass between it and the filling carrier, with the result that ballooning of the thread 20 is practically obviated and the thread is likewise tensioned.

The filling uncoiling control member may be variously formed and preferably, though not necessarily, it should be constituted of 25 fibrous material laid up either as a braided cord or any of the various cordage constructions. The uncoiling control member, regardless of its composition, should be inherently capable of being self-sustained in 30 its operative position in the shuttle, as indicated in Figs. 1 and 2, though it should be sufficiently stable and stiff to assume and maintain the bow construction, as indicated in Figs. 1 and 2, and yet should be sufficiently yieldable to allow the filling to pass 35 between the bow or bend portion of the uncoiling control member and the bobbin without too much or undue retardation.

One good form of the uncoiling control 40 member consists of a braided cord which may be rendered inherently self-sustaining in its operative condition in the shuttle, as indicated in Figs. 1 and 2, by tensioning the yarn elements in the braiding machines, 45 and where the uncoiling control member is formed of fibrous material, either as cord, braid or the like, it may be subjected to a surface treatment of a semi-stiffening compound, such, for instance, as paraffine, wax, shellac, or the like, to impart and insure the necessary self-sustaining character to the 50 uncoiling control member.

The end portions 11 and 12 of the uncoiling 55 control member may be secured to the wall of the bobbin chamber in any desired manner, but, as herein indicated, the ends 11 and 12 of the control member are passed into openings formed in the same wall of the bobbin chamber and wedges 13 and 14 are 60 driven in to secure the uncoiling control

member in its operative position in the bobbin chamber, with the bend of the said member resting upon the filling carrier or bobbin. The term "cord" is herein used in its broad sense to include any of the usual 70 forms of textile braided or twisted elements or even rubber, wire, or other like materials, the essential in this respect being that the uncoiling control member shall be inherently 75 flexible and yielding to permit the discharge of the filling or thread between the bow thereof and the filling carrier or bobbin, and yet shall possess sufficient inherent stiffness or self-sustaining quality to maintain itself 80 in operative position within the shuttle chamber, as indicated in Figs. 1 and 2. This characteristic condition of the uncoiling control member when formed of textile material may be secured during its manufacture by 85 properly tensioning the yarn or threads of which it is composed, and in some cases the inherent stiffness and yet flexibility of the uncoiling control member when formed of textile material may be further enhanced by 90 application of a covering or coating, such as paraffine, wax, shellac, or similar substances, which will not unduly retard the passage of the filling between the bow of the uncoiling control member and the filling carrier or 95 bobbin.

What is claimed is:

1. An automatic filling replenishing shuttle for looms having a bobbin chamber, a filling unwinding control member having its two ends secured to the shuttle body at the same side of the bobbin chamber, and forming an inwardly projecting bowed portion between the ends of the control member unobstructing automatic replenishment of filling and adapted to engage the unwinding filling near the tip end of the bobbin as the filling is withdrawn from the shuttle during weaving.

2. An automatic filling replenishing shuttle having a bobbin chamber adapted to contain a filling carrier or bobbin, and a filling unwinding control cord having its ends secured to the same side of the bobbin chamber at points separated a distance less than the straight length of the cord to provide an inwardly projecting bow or bend in the control cord between its ends for engagement with the unwinding filling near the tip of the filling carrier or bobbin to prevent ballooning while offering no obstruction to the automatic replenishment of filling.

3. An automatically threading loom shuttle having a bobbin chamber, a filling unwinding control member extending in a direction longitudinally of the shuttle at one side of the bobbin chamber and having its ends secured to the shuttle body at the same side of the bobbin chamber, and a bowed portion between the ends of the control member extending inwardly of the bobbin chamber

but not crossing the axis of the filling carrier therein and adapted to engage the unwinding filling near the tip end of the bobbin as the filling is withdrawn from the shuttle during weaving.

4. A filling replenishing loom shuttle having a bobbin chamber to receive a yarn package, a filling unwinding control member having its ends secured to the wall of the shuttle at the same side of the bobbin chamber at one end thereof and provided with a yielding bow or bend between its ends for engagement with the unwinding filling at one side of the axis of the yarn package to permit automatic replenishment of filling.

5. An automatic replenishing loom shuttle having a bobbin chamber to receive a yarn package, a filling unwinding control member having its ends secured to the wall of the shuttle at the same side of the bobbin chamber at points separated a less distance than the straight length of the tensioning mem-

ber to form a yielding bow or bend between the ends of the tensioning member for engagement with the swirling thread as it is withdrawn from the shuttle and permit automatic replenishment of filling.

6. An automatic replenishing loom shuttle having a bobbin chamber, a thread unwinding control member extending in a direction longitudinally of the shuttle at one side of its longitudinal axis and having its ends secured to the same side wall of the bobbin chamber to provide a downwardly yielding bow or bend between said ends projecting inwardly from the side wall of the bobbin chamber to permit the downward passage of a filling carrier from the shuttle and adapted to engage the filling as it unwinds about the end portion of the filling carrier or bobbin.

In testimony whereof, I have signed my name to this specification.

GEORGE H. WILLARD.
